UNITED STATES PATENT OFFICE.

WILLIAM DUBILIER, OF NEW YORK, N. Y.

ELECTRIC HEATER.

1,079,225.

Specification of Letters Patent. Patented Nov. 18, 1913.

Application filed December 19, 1912. Serial No. 737,642.

To all whom it may concern:

Be it known that I, WILLIAM DUBILIER, a citizen of the United States, and a resident of the city of New York, borough of Brooklyn, in the county of Kings and State of New York, have invented a new and Improved Electric Heater, of which the following is a full, clear, and exact description.

10 My invention relates to electric heaters, and the object thereof is to provide an improved radiating element for this class of devices, as well as improved means for supporting the same to enable it to be conveniently used in any location where electric power can be obtained. To this end I provide the heat radiating element which I use in connection with my invention with insulation and engaging devices to enable 15 the element to be readily secured in position; and I also provide a suitable framework made in sections which are held together by fastening devices, the fastening devices being so arranged that they also 20 engage the heat radiating element so as to serve the additional function of mounting the radiating element.

Reference is to be had to the accompanying drawings forming a part of this specification, in which the same characters of reference indicate the same parts in all the views.

Figure 1 is a front view of my invention broken away to show some of the parts in section to illustrate how the heat radiating element is secured in position in the framework; Fig. 2 is a sectional view on the line 2—2 of Fig. 1; and Fig. 3 is a perspective view of the framework in which the 35 heat radiating element is carried.

Referring particularly to the drawings, my invention comprises in general a framework 1, in which is mounted a heat radiating element 2, which is shown in the form 40 of a continuous conductor having a plurality of bends to enable a considerable length of the conductor to be arranged in a relatively small space. These bends are parallel and extend alternately in opposite directions, giving the conductor a zigzag shape, as shown particularly in Fig. 1, and each of the parallel bends forms a radiating section when current traverses the conductor.

The framework 1 comprises a pair of sections 3, one constituting the front and the

other the back of the framework, which is supported upon feet 4, and each of the sections 3 is made up of angle-bars 5 so as to give a section the form of an open rectangular frame. Each section, further, has 60 projections 6 extending from its corners, these projections being perpendicular to the general plane of the section and being L-shaped in cross-section, so that when the sections are fitted together, as shown in Fig. 65 3, the projections 6 of the one will abut upon the projections 6 of the other, forming bars similar to the angle-shaped bars 5, extending between the corners of the sections for a purpose which will be set forth 70 later. Each frame 3 also has a plurality of bosses 7 arranged to extend inward when the frames 3 are secured together to set up the framework, and so located that each of these bosses on one of the frames will be in alignment with one of the bosses on the other frame. The bosses 7 are bored out, one of them being perforated from end to end and the other having a threaded bore to receive and hold the bolt 8. Any number of bosses 80 may be used, but I have shown four as a convenient number, and it will be obvious that when the frames 3 are fitted together, as shown in Fig. 3, and the bolts 8 screwed up, the frames will be secured together and 85 form the framework in which my heating element is located. It will be seen that the framework 1 constructed as outlined above will have its six sides open, and I prefer to close these sides partially by the use of 90 perforated plates 9 at the front and back and a perforated strip 10 bent to form a rectangular frame to fill in the sides, top and bottom of the framework. The angle bars 5 serve to engage the edges of the front 95 and back perforated plates 9, and these angle bars, together with the angle-shaped projections 6, likewise engage the edges of the bent strip 10. These plates 9 and the strip 10 may be secured to the framework 1 100 by any suitable means, and it will be understood that the plates 9 will be suitably recessed so as to give passage to the bosses 7.

The heat radiating element, indicated as a whole by the numeral 2, comprises a continuous length of conductor 11 formed with parallel zigzag bends, as above indicated, and so arranged in the framework that these bends or sections are vertical. Interwoven with these parallel vertical bends are a plu- 110

rality of threads 12 of insulating material which extend across the bends, and the ends of these threads 12 are secured to vertical threads 13 of insulating material arranged 5 along each of the opposite parallel edges of the heat radiating element. These threads 13 are interwoven with the ends of the threads 12, and it will be seen that the threads 12 are arranged in pairs at different 10 places between the top and bottom edges of the heat radiating element, and that along the top and bottom edges I use preferably four transverse threads interwoven with the bends and engaged by the threads 13. These 15 last-named threads are stiffened by immersing the same in a solution of any suitable substance, such as plaster of Paris, to stiffen them and impart to them insulating properties. In order to support this heat radiating 20 element in the framework 1 I employ strips of insulating material 14, such as asbestos, and arrange these strips across the element near the top. I reinforce these strips by means of metallic strips or plates 15, one of 25 which engages the outer face of each strip 14. These strips 14 and 15 have their opposite ends perforated, and the insulation 13 is likewise perforated to give passage to the bolts 8, and it will be seen from the drawings 30 that when the frames are fitted together with the heat radiating element between them in such position that the openings through the strips 14 and 15 and the insulation 13 are in alignment with the bores of the 35 bosses, the bolts 8 will serve not only to secure the frames 3 together, but also to hold the heat radiating element in position.

As stated above, the heat radiating element comprises a single continuous length 40 of conductor, the terminals of which are covered by insulating sleeves 16 and connected to binding posts 17. These binding posts are mounted in the front frame 3 and provided with suitable insulating sleeves 18, and when 45 these binding posts are connected to a suitable source of power, such as an electric lighting circuit, current will pass through the element 11, traveling up and down the bends thereof, entering at one binding post 50 and leaving at the other. During its passage through the element electric power utilized is converted into heat and this heat is radiated through the perforated plates into the apartment.

55 The framework 1 may be made of some suitable metal, such as aluminum, which is light and will not absorb much of the heat which it is desired to generate, and the plates 9 and the strip 10 may be made of similar 60 material. Obviously I may use gauze instead of these plates, and I may also employ any suitable insulating substance instead of the threads 12 and 13. The conductor 11 is made of any metallic substance or alloy 65 which will have the property of opposing

sufficient resistance to the flow of current to cause the element to heat up and radiate heat therefrom.

My heater of course can be made in different sizes to suit the apartment in which the same is to be used. The radiating element does not become incandescent but merely heats up, and this heat is radiated so readily that the effect is soon noticeable. The bars 14 and 15 which engage the heating element 70 near the top thereof serve as an additional supporting means, and if for any reason any of the bends or sections thereof should become distorted or broken, they will prevent contact being made between the same and the framework and the formation of a ground for the current.

75 It will be seen from the above description that my radiator comprises relatively few parts and is exceedingly simple in its construction.

80 The heater can be readily assembled and as readily taken apart for replacement or repair, and the efficiency thereof is such that a marked effect can be produced even by the 85 smaller sizes in which the same may be made.

85 The conducting element 11 which comprises the zigzag bends for forming the heating sections can of course be used in other relations and for other purposes than heating a room. For example, I might use this element as a resistance device to be used in the starting of motors, and in such a case I would make up this element and insulate and support it in the same manner as is 90 shown upon the drawings forming a part of this application.

95 The heating element construction as shown and described is a flexible structure, and in order to be held in proper position it is 10 clamped between the insulation-faced bars 15 that extend the full length of the heating element, gripping the same at all points so as to sustain the weight thereof. It will be observed that the threads 12 extend horizontally so that they do not serve to sustain the weight of the wire or conductor of the element, but simply hold the adjacent vertical sections of the element in spaced relation. If the element were supported only at 11 its ends, as by lugs 7 and bolts 8, the middle of the element would sag on account of its flexibility. The element therefore is supported adjacent its top by the clamping bars 15 that extend from end to end. These bars 1 are comparatively narrow, so as not to materially interfere with the radiation of heat, and only a few rows of threads 12 are employed for the purpose of exposing as great an area as possible of the conductor for the 1 radiation of heat. The heating element in reality is an open-work or mesh structure open at both sides so that heat can radiate in both directions. Since the heating element is supported mainly by the bars 15, the lower set 1

of lugs 7 and bolts 8 serve merely to hold the lower portion of the element steady and in central position.

I wish to have it understood that the foregoing description taken in connection with the drawings discloses but one embodiment of my invention, and I do not care to be limited to the exact details thereof, but reserve to myself the right to make whatever changes in the shape, size and arrangement of the parts fairly fall within the scope and spirit of my invention.

Having thus described my invention, I claim as new and desire to secure by Letters Patent:

1. The combination of a flexible element formed by a conductor bent back and forth into vertical sections, rows of threads of insulation interwoven with the said sections 20 and extending horizontally, and clamping bars disposed between two adjacent rows of threads and at opposite sides of the element and engaging all the sections thereof to support the said element rigidly from end to end.

2. A heating element comprising a conductor bent back and forth into vertically-disposed sections, threads of insulation interwoven with the sections and extending transversely thereto, and sag preventing and clamping elements in the form of bars engaging opposite sides of the element and extending from end to end thereof in the direction of the said threads, in combination with a casing inclosing the element and bars composed of parts clamped together and engaged with the said bars for pressing the bars against the element and thereby holding the same in place.

3. The combination of a casing, a flexible heating element disposed therein, sag preventing and clamping bars secured within the casing and engaging opposite sides of the element adjacent the upper edge thereof 45 to support the weight of the element, and means in the lower portion of the casing for engaging the element to coöperate with the bars for holding the element in position.

4. The combination of a casing composed 50 of separable sections, alining, inwardly-disposed members on the sections, a flexible open-work heating element extending between said members, and a two-part clamping means separate from the element and casing 55 and engaged with the members for engaging opposite sides of the element and extending from one end thereof to the other to support the weight of the element throughout its length.

5. The combination of a heating element having fabric ends of insulation, a casing

inclosing the element, means passing through the fabric ends to hold the element in place, and means held by the first mentioned means for frictionally engaging opposite sides of the element and extending from end to end thereof to support the weight of the element between the fabric ends.

6. The combination of a casing composed 70 of two sections and open at all sides, perforated plates at two opposite sides, a perforated element extending around the other sides and disposed between the first mentioned plates for holding the latter in position against the casing, and fasteners for 75 clamping the two sections together.

7. The combination of a framework comprising a front section and a rear section, each of said sections comprising angle bars 80 to form an open rectangular frame, each of said sections likewise having projections L-shaped in cross-section extending from the corners thereof at right-angles to the plane of the framework, a plurality of bosses carried by each of said sections extending inward of the framework, each boss of one section being in alinement with a boss of the other section, a heating element located between the inner ends of each pair of bosses, 90 said bosses having bores therein to receive fastening means to hold the sections together, and the heating element in position, and perforated plates, the edges of which are engaged by the angle bars and the L-shaped projections to inclose the heating element.

8. The combination of a framework comprising a front section and a rear section, each of said sections comprising angle-bars 100 forming a rectangular frame, and each section having projections L-shaped in cross-section extending from its corners perpendicular to the plane of the frame, bosses carried by each section and arranged to extend inward of the framework, each boss of one section being arranged to be in alinement with the boss of the other section, a heat radiating element arranged between the inner ends of each pair of bosses, said 105 bosses having bores therein, and fastening means received by the bores of said bosses and engaging the heat radiating element to hold the sections together and the element in position.

In testimony whereof I have signed my name to this specification in the presence of two subscribing witnesses,

WILLIAM DUBILIER.
